(57) **CLAIM**

The ornamental design for a disk mastering apparatus, as shown and described.

DESCRIPTION

FIG. 1 is a perspective front view of the disk mastering apparatus of the invention;

FIG. 2 is a rear perspective view thereof;

FIG. 3 is a front perspective view thereof with the front covers removed;

FIG. 4 is a rear perspective view thereof with the covers removed;

FIG. 5 is a top view thereof;

FIG. 6 is a front elevational view thereof;

FIG. 7 is a right side elevational view thereof;

FIG. 8 is a left elevational side view thereof;

FIG. 9 is a rear elevational view thereof;

FIG. 10 is a left side elevational view thereof with covers removed;

FIG. 11 is a rear elevational view thereof with covers removed; and,

FIG. 12 is a bottom plan view thereof.
